Primary Examiner — Mary Ann Calabrese*Assistant Examiner* — Katelin G Kloberg(74) *Attorney, Agent, or Firm* — Gokalp Bayramoglu(57) **CLAIM**

The ornamental design for a feeding bottle, as shown and described.

DESCRIPTION

FIG. 1 is a front view of a feeding bottle showing my new design;

FIG. 2 is a back view thereof;

FIG. 3 is a right side view thereof;

FIG. 4 is a left side view thereof;

FIG. 5 is a top view thereof;

FIG. 6 is a bottom view thereof;

FIG. 7 is a front perspective view thereof;

FIG. 8 is a bottom, front, right side perspective view thereof; and,

FIG. 9 is a top, front, right side perspective view thereof. In the drawings, the broken lines depict portions of the feeding bottle and form no part of the claimed design.

1 Claim, 9 Drawing Sheets(56)
